UNITED STATES PATENT OFFICE.

PERCY E. BARKER, OF CLEVELAND, OHIO, ASSIGNOR TO THE VAN DORN IRON WORKS CO., OF CLEVELAND, OHIO, A CORPORATION OF OHIO.

TAIL-GATE LATCH.

1,383,691.

Specification of Letters Patent.

Patented July 5, 1921.

Application filed June 12, 1920. Serial No. 388,483.

To all whom it may concern:

Be it known that I, PERCY E. BARKER, a citizen of the United States, residing at Cleveland, in the county of Cuyahoga and State of Ohio, have invented a certain new and useful Improvement in Tail-Gate Latches, of which the following is a full, clear, and exact description, reference being had to the accompanying drawings.

10 This invention has for its object the provision of a simple and efficient latch for the tail gates of dump trucks or the like. More specifically it is an object of my invention to provide a tail gate latch that may be 15 adjusted manually from a point adjacent to the driver's seat to permit the gate to be opened to various extents and there held, or to be entirely released, all by a simple sliding movement of the latch relative to 20 the gate.

The invention is hereinafter fully described and a preferred embodiment thereof is illustrated in the drawings. The essential features of the invention are summarized 25 in the claims.

In the drawings Figure 1 is a side elevation of a tiltable body truck equipped with my sliding latch for the tail gate; Fig. 2 is a fragmentary end view of the latch in 30 different adjusted positions, permitting it to vary the rate of discharge through the swinging tail gate; Figs. 3 and 4 are enlarged views in side and front elevation respectively, of the latch operating mechanism; Fig. 5 is a view on an enlarged scale of the latch in coöperation with the tail gate; Fig. 6 is a detail of the supporting connection for the slideable latch, and Fig. 7 is a fragmentary end view of the tail gate 35 and latch. Fig. 8 is a view of the latch plate.

Referring to the drawings by numerals, I have shown my invention applied to the tiltable body 10 on a truck chassis 12. As 40 illustrated the body 10 is supported near the rear end on horizontal pivots 14, and may be tilted about said pivots by suitable hoisting mechanism 15. That shown comprises a plunger 16 adapted to be elevated 45 by suitable means from within a cylindrical

housing 17, which plunger is connected through toggle linkage 18 with the chassis 12 and body 10, whereby the latter may be tilted about its pivots 14 to any degree desired within the limit of movement of the hoisting mechanism. The details of this hoisting mechanism however, constitute no part of this invention but are covered in a separate application.

As shown, the body 10 has a tail gate 20 supported near the top on a pivot 21 and adapted to be held in various positions by my adjustable latch 25. As shown particularly in Fig. 7 the bottom of the tail gate is provided with a length of angle iron 26 extending transversely and projecting laterally as at 27 in the path of the hooked portion 30 of the latch 25.

The latch proper comprises an elongated member 25 having means whereby it may be 70 slidably attached to the truck body. This means may satisfactorily comprise studs 33 projecting outwardly from the bracket 19 and embraced within parallel cam slots 35 in the latch 25. The slots 35 have alined 75 end portions 36 extending longitudinally of the body of the latch and portions 37 parallel to each other extending at an angle downwardly from the portions 36. The slots 35 and studs 33 are positioned relatively to 80 each other in such a manner that the bolts occupy corresponding portions of the slots at all times, the slots being substantially alike. The studs 33 are rigidly secured to a bar 39 by nuts 40 to retain the latch 85 25 in position on the bolts. The intermediate portion of the bolt is shown as of enlarged diameter to provide shoulders abutting the bracket 19, and the bar 39. The bracket 19 may be secured to the body 90 10 by bolts extending through openings 22. As shown in Fig. 8 the raised center portion 23 has tapped holes 24, for securing the latch on the left hand side of the truck. The tapped holes 26 shown in dotted lines 95 are adapted to be used in a bracket positioned on the right hand side of the truck.

Adjustable manually-operable means for actuating the latch is shown particularly in Figs. 3 and 4. A casting 45 may be se- 100

cured as by bolts or rivets through openings 46 to the forward end of the truck body 10, and is provided with spaced segmental portions 48 within which a manually operable lever or handle 49 is pivoted on a shaft 50 within bearings on the casting 45.

Connecting means for the handle 49 and the latch 25 comprises a rock arm 52 keyed to the shaft 50 and pivoted at 53 to an arm 54 which is connected to the latch 25 by a rod or link 55. The arm 54 is shown having one end flattened and curved as at 56 while the other end 58 is hollow and internally threaded to receive the threaded end 59 of the rod 55. The other end of the rod 55 may be threaded within an open hollow end of a clevis-like member 63 pivoted at 64 to the end of the latch 25. Lock nuts 60 may be provided on the rod 55 to retain the same rigidly in adjusted positions within the members 54 and 63.

The segmental members 48 are provided with a series of spaced registering openings 66, the different pairs being adapted to be selectively occupied by a pin or bolt 67 to support the arm 49 in various positions of adjustment.

As will be observed in Figs. 1 and 5 the portions 36 of the slots 35 are not horizontal nor are the studs 33 located in a horizontal plane. The rear stud 33 is positioned slightly above the forward one, and the slots 36 inclined upwardly slightly toward the rear in order to permit the latch 36 to slide in a direction parallel to the line A-B representing the chord subtending the arc traversed by the upper edge of the angle iron 27 as it swings with the tail gate about the pivot 21. With this arrangement the clearance between the upper edge of the projection 27 and the shank of the latch adjacent to the hook 30 may be merely nominal, since rearward movement of the latch 25 as the tail gate swings open will not tend to cause binding between the angle bar and latch, as would otherwise be the case.

In use and operation the rod 55 is adjusted to permit the operating handle 49 to be in its highest position as illustrated in Figs. 3 and 4, when the tail gate 20 is closed, with the latch 25 in the position illustrated in Fig. 5, wherein the studs 33 occupy the rear or right hand ends of the slots 35. When it is desired to dump the load the rate of discharge may of course be varied by varying the amount of opening of the tail gate, which is done by removing the pin 67 and inserting it in a lower pair of openings 66, permitting the handle 49 to be lowered with a consequent movement of the latch 25 rearwardly permitting the tail gate to become opened a certain amount. The latch 25 may be set with the bolts 33 occupying various positions along the portions 36 of the slots 35, as shown in Fig. 2 depending upon the

rate of discharge desired when the truck is elevated to dumping position.

If it is desired to open the tail gate to the full extent the latch may be moved rearwardly by setting the handle 49 downwardly until the portions 37 of the slots 35 engage the bolts 33 thereby causing the latch 25 to travel bodily upwardly and rearwardly at an angle to its former course until the hooked end 30 is released from the projecting end 27 of the angle iron, thereby permitting the tail gate 20 to swing freely as illustrated in dotted position in Fig. 1.

Having thus described my invention I claim:—

1. In a device of the character described, a body having a pivotally mounted tail gate, a latch for holding the same, said latch being mounted at the base of the body, and means for manually adjusting and holding the tail gate in partially opened position, and thereafter freeing it by moving said latch while maintaining it at all times parallel to itself, said latch being operable independently of the position of the truck body.

2. In combination, a tiltable truck body having a side wall and a tail gate, a latch for the gate slidably secured to said side wall through a cam slot in the latch and a pin connection secured to the wall of the body.

3. In a device of the character described, a latch comprising a hook having a plurality of cam slots in the shank portion thereof.

4. A tail gate latch comprising a member having a shank portion and a hooked end, a pair of equal bent slots in the shank portion, said slots having mutually aligned portions and parallel offset portions therefrom.

5. A tail gate latch comprising a member having a shank portion and a hooked end, a plurality of angular cam slots in the shank portion, said slots having parallel portions at an angle with the shank portion of the latch and extending from the same side of the shank portion as does the hook.

6. In a device of the character described, a tiltable truck body, a hinged tail gate, a latch mounted on the side of the body having a hooked end adapted to engage the gate, a manually operable lever, and means connecting said latch and said lever, the latch being so mounted that it may be moved upwardly and rearwardly while remaining parallel to its original position to open the tail gate varying amounts.

7. In a device of the character described, a tail gate hinged to the rear of a tiltable truck body, a latch for the same, comprising a member having cam slots, projections carried by the truck body embraced by said slots, said latch having a hooked end adapted to engage a portion of the gate remote

from the hinge, and means for sliding said latch on said projections.

8. A tail gate latch comprising an elongated member, having a downwardly extending hooked end, a plurality of equiangular slots in the shank portion of the member, said slots being positioned one in

front of the other, and projections adapted to be embraced by said slots whereby the latch is slidably supported.

In testimony whereof, I hereunto affix my signature.

10

PERCY E. BARKER.
